UNITED STATES PATENT OFFICE.

PETER SWANSON, OF ELY, MINNESOTA.

SWITCH SIGNAL.

Application filed November 5, 1925. Serial No. 67,064.

This invention relates to switch signaling devices and has special reference to a novel arrangement of target and lamp for railroad switches.

5 The principal object is to provide a more efficient and reliable signaling device for such switches.

Another object is to provide means whereby to prevent accident in the event of the 10 switch being left unlocked even though not thrown to dangerous position.

Another object is to provide an auxiliary 15 target for the common railroad switch affording the additional advantages to such common switch above set forth.

Other objects and advantages will appear in the further description of the invention.

Referring now to the accompanying drawing, forming part of this application, and in 20 which like reference characters indicate like parts:

Figure 1 is an elevation of the switch target, or signaling device in an all clear position;

25 Figure 2 is a similar view showing the danger signal in the event of the switch being left unlocked even though turned for all clear position for the main line;

Figure 3 is a similar view illustrating the 30 target and lamp signaling that the siding is open, or danger for the main line;

Figure 4 is a modified form of mounting of the novel signaling device on the switch target;

35 Figure 5 is an enlarged transverse sectional view of the automatic lock; and

Figure 6 is a similar view partly in section taken on line 6—6, Figure 5.

At 1 is illustrated an ordinary switch 40 stand, provided with an opening lever or switch handle 2, pivoted as at 3, to the supporting links 4, and by which the switch is thrown, the lever 2 being pivoted as at 5 upon the switch stock 6, which is rotated 45 in either direction when the lever is raised subsequent to the unlocking of same.

In my present invention the locking lug 7 is formed with a channel or notch 8 upon one side thereof for the reception of the 50 auxiliary target operating rod 9.

10 represents a common switch target mounted upon the staff 11 and the auxiliary target rod is held in permanent relation thereto by means of the strap bearing 12 55 clamped about the staff 11 just above the stock 6, so that the lower end of the target

rod 9 is at all times held in position within the notch or channel 8 in the switch lug, though of course permitted to reciprocate freely vertically.

Upon the upper spaced extremities of the common signal target 10 is attached the auxiliary target, it being in cross-sectional appearance of inverted U-shape, the two vertical walls being in the form of an arrow 65 as illustrated at 13, and the horizontal or intermediate portion being flat and rectangular in shape as indicated at 14, it extending beyond the head of the arrows 13. The pivotal connection of the auxiliary target 70 with the common upright one is indicated at 15, the same occurring on the shafts of the arrows 13 and upon suitable angularly shaped clips or lugs 16 which are riveted to the corners of the common target. 75

The rod 9 for operating the auxiliary target is pivotally connected as at 17 to a rearwardly projecting arm or lug 18 at the rear of the auxiliary target and adjacent the switch staff 11. By this means it is 80 apparent that when auxiliary target is in the position shown either in Figures 1 or 2 the rod 9 will be in its depressed or lowermost position, while when the auxiliary target is down showing a dangerous condition of the switch the rod 9 will be in its most elevated position.

To the rearmost edge of the central portion 14 of the auxiliary target are attached two rearwardly projecting lugs indicated at 90 19 and to which lugs are attached the lugs 20 of the lamp screen 21. This screen is mounted in such a manner as to vertically reciprocate in front of and formed to act as a screen for the lantern 22, it having a 95 lowermost hole in it covered with a red glass as indicated at 23, and an uppermost hole covered with a green glass as indicated at 24, so that when the auxiliary target drops the screen or shield 21 will be raised bringing the red light 23 in front of the lantern thus showing a red light to coincide with the danger signal. This screen 21 may be held in upright position in any desired manner, as for example by the forked bracket 100 25 rigidly fixed as at 26 to the switch staff 11.

The application of my improved auxiliary target above described is that of one applied to a common switch target as used on some railroads, for example, in the State 105 of Minnesota, where the face appearance of the common target indicates a clear right 110

of way. This, however, not being universal railroad practice I have provided a modified installation of my auxiliary target as shown in Figure 4 of the drawings, where the target is of the same construction as above described, except that it is mounted upon and at right angles to the common target, the same requiring angular brackets 27 upon the target staff 11 for the pivotal support of the auxiliary target which as before stated is identical with and of the same construction as that shown in Figures 1, 2 and 3, it carrying the two spaced arrows 13 and intermediate portion 14, and is operated in identically the same manner.

The common target in this instance is indicated at 28, it presenting an edge view instead of a front or back view in respect to the mounting of the auxiliary target, the lantern and its control being identical to that shown in the other figures of the drawings.

Mounted upon the operating handle 2 is a lock housing indicated at 29, which contains the automatic locking device, the latter comprising the horizontally operated crooked finger shaped bolt 30 pivotally mounted upon the vertically disposed pin 31, said bolt being held in locked position as shown in Figure 5 by means of the expansive helical spring 32 which presses against a suitable step in the side wall of the housing 29 at one end and against the handle end of the bolt 30 at the opposite end, and controlled oppositely, or opened, by the key 33. This key is of the ordinary type and pivots upon the pin 34 suitably mounted within the lock.

The locking terminal of the bolt 30 is rounded in shape as at 35 so as to slip conveniently past the bevelled or rounded end 36 of the lug 7 of the switch stand, so that when the handle 2 is raised upwardly away from the lug 7 of the switch stand and is forced into locked position by the action of the spring 32 it will slip by the end of the lug 7 when the handle is depressed ready for automatic engagement within the registering holes of the target operating rod 9 and the lug 7; the former,

of course, having to be drawn downwardly by hand into such registering position before the switch will or can be locked. Thus, if left unlocked, the auxiliary target will show danger.

There is a shield illustrated at 37 carried by the target operating rod 9 to normally cover the opening in the lock to protect it against rain, etc.

It will be noted that the target operating rod 9 is provided with an offset or stepped portion 38, which provides convenient means for grasping same during manipulation thereof, and also prevents the rod being lowered while the handle is in raised position, the elbow formed by such offset engaging one side of the bifurcated handle 2 if attempt is made to lower it while the handle is raised.

Having thus described my invention, what I claim and desire to secure by Letters Patent, is:

1. The combination with a common railroad switch stand having a pivotally mounted switch handle for manipulation thereof, of an auxiliary target mounted upon said switch stand connected to and operable by the switch handle, and means for automatically locking the auxiliary target and the switch handle.

2. The combination with a railroad switch stand carrying an auxiliary target thereupon and lock therefor and an operating or switch handle, of means for operating the auxiliary target operable by said handle, means whereby unlocking of the said handle automatically operates the target, and means for automatically locking the said handle and auxiliary target.

3. In combination, a railroad switch having a common target, an auxiliary target pivotally mounted upon the common target, a lock carried upon the switch handle a rod for operating the auxiliary target operable by the locking and unlocking of the switch.

In testimony whereof I hereunto affix my signature.

PETER SWANSON.
